UNITED STATES PATENT OFFICE.

LLOYD BLACKMORE, OF HIGHLAND PARK, MICHIGAN, ASSIGNOR TO GENERAL MOTORS CORPORATION, OF DETROIT, MICHIGAN, A CORPORATION OF DELAWARE.

LAMP.

Application filed May 2, 1923. Serial No. 636,228.

This invention relates to lamps and several modifications are illustrated as embodied in the headlights of an automobile. An object of the invention is to construct the reflector of such a lamp to serve as the "door," or removable front, of the headlight.

From this point of view the invention contemplates forming the reflector, which is preferably of metal such as duralumin, to permit the supporting of an electric bulb or light substantially at its axis. The reflector may form the body of the lamp or may be removably mounted in the open end of an enclosing shell, and in the preferred form of the invention the reflector is doubled back on itself to form an encircling frame or bezel for the glass front. In one illustrative embodiment of the invention this doubled back portion forms a cylindrical flange which engages an annular ridge on the shell to give the lamp a finished appearance.

The reflector is removably secured in the shell by a member which may also, if desired, be used to secure the usual glass or lens in the open end of the reflector. In one arrangement selected for illustration this member is in the form of a spring ring having offset portions which project through aligned openings in the reflector and the shell and which may be seated in a groove formed in the reflector, projecting sufficiently therefrom to hold the glass in place against an annular shoulder formed in the reflector.

Another feature of the invention relates to an arrangement for supporting the socket for the electric connections on the reflector, or for passing the connecting wires through the lamp support to a socket carried by the support. Other features and objects of the invention, including a new connection for the tie rod and various other novel combinations of parts and desirable particular constructions, will be apparent from the following description of the illustrative embodiments shown in the accompanying drawings, in which:

Figure 1 is a view of a headlight in front elevation, with parts broken away and shown in vertical section on the line 1—1 of Figure 2;

Figure 2 is a section substantially on the line 2—2 of Figure 1 showing the manner of securing the reflector in the open end of its shell;

Figure 3 is a front elevation of a modified form;

Figure 4 is a vertical section on the line 4—4 of Figure 3;

Figure 5 is a front elevation, partly broken away, of a differently-modified form; and

Figure 6 is a view, partly in side elevation and partly in vertical section, of the modification shown in Figure 5.

In the first illustrative embodiment of the invention the parts are enclosed in a shell 10, which has a centrally arranged socket 12 to permit connection to an electric circuit. The socket 12 is connected to an inner socket 14 which carries the bulb or light 16, the socket 14 being arranged in an opening substantially at the axis of a reflector 18 of duralumin or other metal which is drawn or otherwise pressed to provide a substantially parabolic reflector portion in which the bulb is mounted, and which is bent back on itself at 20 to form a substantially cylindrical flange which engages an annular ridge 22 on the shell 10 to provide a finished pleasing appearance on the exterior of the lamp. The usual glass or lens 24 may be seated against a gasket or rubber washer 26 engaging a shoulder formed in the reflector 18, and it is held in place by a spring wire 28 which is seated in a groove formed in the reflector, but which projects from the groove sufficiently to hold the glass in place. The reflector and shell are provided with aligned openings 30 through which project offset portions 32 of the spring wire 28, thus locking the reflector and shell effectively together by means of the member which holds the glass or lens 24.

The modification shown in Figures 3 and 4 differs from that of Figures 1 and 2, in that the casing 110 does not carry the socket 112 for the electrical connections, the socket being mounted at the bottom of the flange 120 of reflector 118, and being connected to the bulb 116 in socket 114 by wires 117. The glass 124 is provided with a gasket or washer 126, which may be of rubber, and which is U-shaped in cross section to embrace the edge of the glass, and is held in place by a spring wire 128 which may have offset portions 132 snapping into holes in the reflector 118. The reflector 118 is shown as being secured to casing 110 by rivets 134.

One manner of supporting the lamp is

also shown in Figures 3 and 4, the reflector, in forming flange 120, being bent to inclose a support such as an arcuate rod 136 having a stem 138 projecting through a hole in flange 120 and threaded to receive a clamp nut 140. This nut engages a frusto-spherical washer 142, which cooperates with a concave washer 144 pinned to stem 138, in such a manner as adjustably to clamp the lamp on a bracket 146. A lock washer 148 may also be provided. Bracket 146 has an arm 150 to be bolted or riveted to the fender, and an arm 152 bolted or otherwise secured to a tie rod 154, shown as a tubular member, which is similarly connected to the bracket 146 of the opposite lamp.

In the modification shown in Figures 5 and 6, casing 210 is in the same form as casing 110 shown in Figures 3 and 4, and does not carry the socket 212 for the electrical connections. The socket 214, carrying the bulb 216, is mounted in the lower part of reflector 218, to make the connection 217 as short as possible. The flange 220 of reflector 218 may be riveted or otherwise secured to casing 210. Glass 224, with its gasket 226 of U-shaped cross-section, is held in place by spring wire 228.

In this modification the connecting wires 217 pass through a hole in the rear of rod 236, and through stem 238, which is hollow, to socket 212, which is secured to or integral with nut 240. Nut 240 cooperates with convex washer 242 and concave washer 244, the latter being shown as adjustably threaded on stem 238, to clamp the lamp on bracket 246, with or without lock washer 248. Bracket 246 has an arm 250 to be secured to the fender. The rod 236 is extended to form a portion 252 projecting through a hole in flange 220, and which is connected by a tie rod 254, shown as a tubular member, to the opposite lamp.

While illustrative embodiments of my invention have been described in detail, it is not my intention to limit its scope to those embodiments or otherwise than by the terms of the appended claims. It is to be noted

that, while not in all of its aspects necessarily limited thereto, the invention is especially useful in lamps which are provided with reflectors of duralumin or an equivalent material which does not tarnish and which can readily be worked into the required form and which provides a surface of pleasing appearance on the parts which extend beyond the glass or lens 24 and which are therefore exposed.

I claim:

1. A lamp comprising, in combination, an outer shell, a reflector in the shell having a backwardly bent portion fitting over the edge of the shell, and a locking ring within the reflector having offset portions projecting through alined openings in the reflector and the shell to fasten them together. 60

2. A lamp comprising, in combination, an outer shell, a reflector in the shell, a glass in the reflector, and a locking ring having offset portions projecting through alined openings in the reflector and the shell to lock the reflector in the shell and the glass in the reflector. 70

3. A lamp comprising, in combination, an outer shell, a combination door and reflector mounted in the open end of the shell, a glass mounted in the open end of the reflector, and common means for securing the glass in the reflector and the reflector in the shell. 75

4. The combination of a lamp casing having a forwardly projecting portion defining an open end, a reflector fitting in the open end of said casing having a turned-back outer edge forming a channel in which the forwardly projecting portion of said casing is received, means engaging the inner wall of said channel and the forwardly projecting portion of said casing for securing the reflector in the casing, and a transparent medium for the open end of the said reflector held in position by said last-named means. 85

In testimony whereof I affix my signature.

LLOYD BLACKMORE.
